(Continued)

FIG. 1 is a front perspective view showing my new design, with a central region of the panel that forms no part of the claimed design shown by broken lines indicating that the panel is of an indefinite length;

FIG. 2 is a rear perspective view thereof;

FIG. 3 is a front elevational view thereof;

FIG. 4 is a top view thereof;

FIG. 5 is a bottom view thereof;

FIG. 6 is a right end view thereof, it being understood that a left end view would be a mirror image of the right end view; and,

FIG. 7 is a sectional view, on an enlarged scale, as seen from a plane indicated by a line 7-7 in FIG. 3, showing a bracket shaped like the numeral "7."

The design relates to opposite end regions of a side panel used in forming a pipe trench, in which the end regions have an identical but mirror image appearance, and are connected by intervening structure that forms no part of the claimed design. All subject matter depicted by broken lines is environmental, is provided for merely for illustrative purposes, and forms no part of the claimed design.
